INVENTOR.

BY Thomas H. Conway, Sr
William M. Swan
ATTORNEY.

UNITED STATES PATENT OFFICE.

THOMAS H. CONWAY, SR., OF DETROIT, MICHIGAN.

DAMPER.

Application filed April 19, 1923. Serial No. 633,053.

To all whom it may concern:

Be it known that I, THOMAS H. CONWAY, Sr., a citizen of the United States, residing at Detroit, county of Wayne, State of Michigan, have invented a certain new and useful Improvement in Dampers, and declare the following to be a full, clear, and exact description of the same, such as will enable others skilled in the art to which it pertains to make and use the same, reference being had to the accompanying drawings, which form a part of this specification.

This invention relates to a "damper" for flues, and has for its object an improved construction whereby not only may the degree of opening or closure of the damper be easily and accurately regulated from without, as for example a point on the front or exposed surface of the grate wall, but it concerns as well the pivoting of the damper plate in such a way that, when thrown open, substantially the entire cross-sectional extent of the flue may be rendered available for the upward passage of the products of combustion without splitting the draft, that is, requiring that the upward air current be divided so as to pass on each side of a centrally pivoted damper plate.

Figure 1 is a perspective of my improved construction with the damper plate shown in almost fully open position.

Figure 2 is a vertical cross-sectional view, with the damper in closed position.

Figure 3 is a similar cross-sectional view, taken along the line 3—3 of Figure 1, showing the damper in raised position.

Figure 4 is a fragmentary elevational view of the damper plate and of the cam viewed from the opposite direction from that from which Figure 1 is taken.

Figure 5 is an edge elevational view of the cam on a somewhat enlarged scale.

A represents a rectangular dome frame for a flue with its bordering edges A' adapted to be built into the wall. The tapering side walls A² have their end sections provided with sockets B, in which are journaled the trunnion ends C which project from correspondingly located positions on the ends of the damper plate D. A ridge or rib F is preferably located on the under side of the damper plate D in such position as to be engaged by the notched surface of the eccentric or cam piece G, which is carried on the inner end of the shaft H. This

latter rotatably engages through the bearing J in the flue wall, and on its outer end is mounted the handle K, by means of which its rotative actuation may be accomplished when the opening or closing of the damper plate is desired.

When the plate D is in closed position across the throat of the flue, the wiping edge of the cam G engages the rib F with a point on its periphery which is located relatively near to the shaft J; and its point of contact with the rib F is relatively near the front or free edge of the plate D. When, however, the shaft J is rotated, the increasing eccentricity of the peripheral edge of the cam which is drawn against the rib F results in raising of the free edge of the plate about its trunnion projections B as a center. It is in the early stages of the lifting movement that the greatest lifting force of the cam upon the plate is required, and consequently its positioning near its forward unpivoted edge is desirable. When, however, the lifting of the plate, through a 45 degree angle for example, has been effected, this factor diminishes, the principal requirement then being a tendency to throw the plate D back to a vertical position; to care for this, that portion of the cam lying, for example, between the peripheral points X and Y is inclined away from the plane of the portion of the cam which was first active, thus not only more closely following the rib F as it is raised and thrown backward, but its point of frictional engagement therewith actually traveling along the rib F toward the rear or pivoted edge of the plate D, so as to effect a greater throw of the pivot plate in degrees proportionately to the degree of turning of the pivot H than is the case in the earlier lifting stages. Similarly when the closure movement of the plate is desired, the reverse of this described action as regards the wiping movement of the cam's periphery against the rib F takes place.

The plate D is preferably not designed to be raised to quite a fully vertical position. The difference in the cross-sectional area of the open part of the flue throat is so slight, however, as to be negligible, and in any event is much less than the diminution in the cross-sectional area of the flue throat in case the damper plate D is centrally pivoted, as has heretofore been the practice, so that the upwardly traveling current of

the products of combustion was forced to divide as it passed the centrally pivoted plate, thereby effectually lessening the clearness of the draft.

5. What I claim is:

1. In combination with a rectangular dome frame, a closure plate having trunnion connections therewith adjacent one of its lateral edges, whereby the swing of the plate 10 thereabout toward the side of the flue throat permits the central flow of the draught therethrough, and an externally actuatable cam member, whose axis of rotation is disposed transversely to that of the trunnion 15 connections of the plate, and is adapted to liftingly engage the under face of the plate, that portion of the cam which engages the plate in the later stages of its rotative actuation being bent away from the plane of 20 the central portion, whereby it engages points on the under surface of the plate increasingly near its trunnion axis as the lifting movement progresses.
2. A dome damper, having, in combination 25 with a laterally pivoted closure plate adapted to regulate the possible draught flow through a chimney flue, an externally actuatable cam therefor whose plane is generally parallel to the axis of turning of said 30 closure plate, certain portions of the engaging periphery of said cam being bent away from the plane of the remainder thereof, whereby, as it is rotated, the point of its contact with the under surface of the 35 plate moves toward the rotative axis of the plate during its lifting and away therefrom as the plate is lowered toward closure position.
3. A dome damper, having, in combination 40 with a closure plate adapted to turn

about the axis of pivoting projections adjacent the ends of one of its lateral edges, an externally actuatable cam member adapted to liftingly engage the under face of the plate, a portion of the peripheral edge of 45 said cam member being so bent relatively to the plane of the remaining portion thereof that as the cam is rotated the point of its contact with the under face of the closure plate moves transversely of the axis of turning thereof.

4. The combination, with a rectangular flue throat, of a laterally journaled closure plate therefor, and an externally actuatable cam member adapted to frictionally engage 55 the under side of said closure plate to effect its upward swing, said cam having that portion of its body containing its highest point curved from the plane of its center portion in a direction to cause additional 60 rearward throw to the closure plate as its opening movement approaches its maximum.

5. In combination with a closure plate journaled to swing approximately about one 65 of its long sides as an axis, a lifting cam adapted to liftingly engage the under face thereof from a point near its free side toward its journaled side, the outer peripheral portion of the cam being inclined away from the center portion to bring about 70 added throw of the plate toward its extreme upper position as the lifting movement progresses.

In testimony whereof, I sign this specification in the presence of two witnesses.

THOMAS H. CONWAY, Sr.
